FRANK B. WILDMAN AND GEORGE L. BALLARD, OF NORRISTOWN, PENNSYLVANIA,
ASSIGNORS TO WILDMAN MFG. CO., A CORPORATION OF PENNSYLVANIA.

KNITTING-MACHINE.

1,127,385.

Specification of Letters Patent.

Patented Feb. 2, 1915.

Application filed November 9, 1912. Serial No. 730,510.

To all whom it may concern:

Be it known that we, FRANK B. WILDMAN and GEORGE L. BALLARD, a citizen of the United States and a subject of the King 5 of Great Britain, respectively, residing at Norristown, Pennsylvania, have invented certain new and useful Improvements in Knitting-Machine Latch-Openers, of which the following is a specification.

10 The invention has for its object to provide a brush for opening the latches of the needles, which will be in position to receive the needles at such times that the latches must be opened, but which will be out of 15 contact with the needles when not needed to perform its function, thus avoiding excessive wear on the brush and its frequent renewal.

In the accompanying drawings is shown 20 in Figure 1 a brush with automatic controlling mechanism applied to a knitting head of one type designed to produce a welt and having a clearing course cam; Fig. 2 is an elevation of the head; Fig. 3 is a plan 25 view of the invention applied to another form of knitting head, and Fig. 4 is a side view of the head of Fig. 3 with some of the parts omitted.

Referring to Fig. 1, the brush and automatic controlling or positioning mechanism there shown is applied to the type of machine in which the cams rotate and are controlled as to their positions by contact arms, which strike a roller on the fixed base, which 30 is raised and lowered into the plane of the arms by pattern mechanism. In the drawings, 1 indicates the cylinder cam ring and 2 the dial plate rotating in the arrow direction. 2' is the thread guide; 3 the advancing 35 cam of the dial, and 4 the dial post of the clearing cam of the cylinder needles. This post has a pin 5 under which moves the incline 6 of a cam disk 7 when said disk is turned by the arm 8 striking the controller roller 9 on the fixed frame. This 40 arm 8 is on a shaft 10 geared at 10°, Fig. 2, as is well known in the art, to a shaft 11 which has the cam disk 7 fixed thereto. A returning arm 12 fixed to the shaft 11, when 45 it strikes the controller roller turns the cam disk to remove its incline 6 from beneath the pin to allow the cam to move down again under the action of a spring (not shown), which presses upon the post. 50 When the cam is up, the needles are ad-

vanced far enough to get the loops back of the latches, and in retracting these needles knit off. These empty needles, when advanced to again take the thread, require that their latches be open, and to insure this 60 open position of the latches the brush 23 is provided carried upon an arm 13 pivoted at 14 to the dial cap, and having a pin 15 to be struck by a pin or projection 16 carried by the shaft 11 of the disk cam 7. When 65 the cam disk is turned to raise the clearing course cam of the cylinder, the pin 16 strikes pin 15 and moves the arm or plate 13 to swing the brush 23 over the cylinder needles so that the empty needles, in passing 70 between the bristles, have their latches opened prior to taking the thread from the guide 2'. The clearing course is formed just before the welt is begun. As soon as the dial advancing cam 3 is moved inwardly 75 to retract the dial needles for the formation of the welt, the brush is moved from over the cylinder needles. The dial advancing or wing cam is operated by a link 18 having a pin 19 passing through a slot 17 in the 80 dial cap, said link being connected adjustably to a segmental arm or plate 20 on the shaft 21. This shaft is turned one way by an arm 22 thereon striking the controller 85 roller 9. This sets the advancing cam 3 inwardly, and at the same time a pin 24 on the extension 25 of the shaft 21 contacts with a pin 26 on the brush carrying arm 13, so that this is turned to the position shown in Fig. 1, and the brush is removed from the 90 needles, where it remains until another clearing course is to be made, when the operations above outlined will be repeated. The arm 13 is under restraint of a spring 13'. The advancing cam 3 is returned outwardly and the pin 24 removed from the pin 26 by the arm 27 striking the controller roller.

In Figs. 3 and 4 we illustrate another application of our invention, *i. e.*, to a different form of knitting head. Here the brush 23' is carried by a rock shaft 28 journaled in a bracket 29 fixed on one of the posts 30 of the head. The rock shaft is turned by a spring 31 to carry the brush 105 into position over the needle circle, the spring being attached at one end to the bracket and at the other end to a collar 31' on the shaft. The shaft also has an arm or pin 32 depending therefrom to be engaged 110

by an arm or pin 33 on the shaft 34. This shaft carries the arm 35 having studs 36 for pressing the head 37 downwardly by working on inclines 39 on said head. This 5 head is attached to the post 40 of the cylinder stitch cam. When the slack is to be knit to make the welt, the arm 35 is moved in removing the pin 33 from the pin of the brush shaft, which is then turned by the 10 spring to present the brush over the needle circle. As soon as knitting of the welt is completed, the slack is thrown off and the brush is removed. The operation just stated of throwing the brush in results from the 15 arm 41 striking the pattern controlled roller 9', and for throwing the brush out the arm 42 strikes the said roll. The last mentioned arm 42 is fixed to the shaft which carries the arm 35, whereas the arm 41 is on a separate shaft geared to the first shaft, as is 20 well known in the Wildman type of knitting machine.

From the above it will be seen that the brush is thrown into position to act on the 25 needles only when necessary to perform its work. At all other times the brush is free from the wear of the needles running through it.

We claim as our invention:—

30 1. In combination in a circular knitting machine, latch needles, a rotary cam box, adjusting mechanism for one of the cams comprising a rotary shaft mounted vertically in the cam box, and having means for 35 adjusting the cam vertically, a brush to open the latches of the needles and movable in relation to the needles, an operating connection between said brush and the vertical shaft, and means for operating the shaft as 40 the cam box revolves, substantially as described.

2. In combination in a circular knitting machine, latch needles, a rotary cam box,

cam adjusting mechanism carried thereby comprising a vertical rock shaft and means 45 attached thereto for moving one of the cams vertically, a brush to open the latches of the needles and movable in relation to the needles, a holder for said brush having back and forth movement, and a laterally extending arm on the rock shaft for operating the said holder, substantially as described. 50

3. In combination in a circular knitting machine, needles, a rotary cam box, adjusting mechanism for one of the cams comprising a rotary shaft mounted vertically 55 in the cam box and having means for adjusting the cam vertically, a horizontal shaft mounted to revolve with the cam box, a brush depending therefrom and a connection between the horizontal shaft and the vertical shaft for adjusting the brush in relation to the needles when the needle cam is adjusted, substantially as described. 60

4. In combination in a circular knitting 65 machine, needles, a rotary cam box, cam adjusting mechanism carried thereby, comprising a vertical rock shaft and means attached thereto for moving one of the cams vertically, a brush movable to and from 70 the plane of operation of the needles, a horizontal shaft carrying the said brush, a pin depending from said horizontal shaft, a laterally extending pin on the vertical shaft to engage the depending pin for turning the horizontal shaft in one direction, and a spring to turn the horizontal shaft in the other direction, substantially as described. 75

In testimony whereof, we affix our signatures in presence of two witnesses.

FRANK B. WILDMAN.
GEORGE L. BALLARD.
